Henry W. Kenyon

UNITED STATES PATENT OFFICE

MAX REINER, OF BRONX, NEW YORK, ASSIGNOR TO PERPETUAL SELF WINDING WATCH COMPANY OF AMERICA, INC., OF NEW YORK, N. Y., A CORPORATION OF DELAWARE

SELF-WINDING WATCH

Application filed November 12, 1929. Serial No. 406,561.

This invention relates to watches and more especially to wrist watches equipped with means for effecting winding of the main spring upon movement of the watch.

5 An object of this invention is a self-winding watch provided with improved and effective means for winding the main spring upon movement of the watch while being worn and preventing overwinding of such 10 spring.

In a watch embodying this invention there is provided a weighted pendulum which is caused to oscillate by movement imparted to the watch usually while being worn. A pivoted lever is provided which is equipped with means for imparting uni-directional rotation to a wheel associated with the winding train of the watch. Resilient means are provided to cause the lever to move in unison with the 15 pendulum in one direction and gravity is relied upon to move the lever and pendulum in unison in the opposite direction. The tension of the resilient means is such that when the main spring is nearly wound, oscillation 20 of the pendulum without corresponding oscillation of the lever is permitted, thus preventing overwinding of the spring. Means are provided for varying the tension applied to the resilient means, thus making it possible to vary the extent to which the main 25 spring is wound.

Other objects, novel features and advantages of this invention will be apparent from the following specification and accompanying 30 drawings, wherein:

Fig. 1 is a rear view of a watch embodying the invention, and

Figs. 2, 3 and 4 are detail views of modified forms of the pendulum mechanism.

40 Referring now to Fig. 1, the case 10 may be of any suitable design and within it is suitably arranged the watch movement 11. The main spring gear wheel 12 is connected through a suitable winding train with a ratchet wheel 13, the reverse operation of which is prevented by the pawl 14. A pivoted lever 15 is provided with a spring pressed pawl 16 which engages the teeth of the ratchet wheel 13 to impart uni-directional 45 rotation thereto upon oscillation of the lever.

A weighted pendulum is pivoted for oscillation about a different axis than the axis of the lever 15 and the extent of oscillation of the pendulum may be limited by stops 18. A resilient member or spring 19 is pivoted to 55 the end of the lever 15 and one end of this member engages a pin 20 carried by the pendulum 17. The other end of the resilient member engages an adjusting screw 21.

Counter-clockwise movement of the pendulum 17 causes corresponding movement of the lever 15 and return movement of the pendulum and lever is effected by gravity. Movement of the watch thus normally causes 60 corresponding oscillation of the pendulum and lever. Counter-clockwise movement of the lever 15 causes counter-clockwise rotation of the ratchet wheel 13 thereby effecting winding of the main spring through the medium of the winding train. However, should the main spring be nearly wound up, its resistance to winding will be sufficient to 65 overcome the tension of the spring 19 so that the lever 15 will remain stationary during oscillation of the pendulum 17. The tension exerted by the spring 19 may be varied by 70 adjusting the screw 21.

In Fig. 2, the lever 15 and pendulum 17 have a common axis. The operation of the pendulum and lever is, however, the same as 75 in Fig. 1.

In the modification disclosed in Fig. 3, the lever 15 and pendulum 17 have separate axes and the resilient member 19 is carried by the pendulum. One end of the resilient 80 member 19 extends between pins 20 on the lever 15 and the other end engages a hexagonal adjusting member 21a. The operation in this modification is similar to that of the 85 operation of the embodiment disclosed in 90 Fig. 1.

In the modification disclosed in Fig. 4, the pendulum 17 is pivoted to the lever 15 and the spring 19 is carried by the lever 15. One end of the spring 19 engages a pin 20 carried 95 by the pendulum while the other end engages the hexagonal adjusting member 21a. In this modification, the lever and pendulum swing in unison except when the resistance to winding overcomes the tension of the 100

spring 19, when the lever 15 remains stationary and the pendulum 17 oscillates relative thereto.

The spring 19 tends to keep the lever 5 and pendulum in definite relationship and also tends to restore the relationship whenever the pendulum is moved away from the lever. There is no drag exerted on the pendulum tending to retard its return to normal position. Rather, there is exerted on the pendulum a force tending to assist its return to normal position. The force exerted by the spring tending to oppose movement of the pendulum away from the lever is definitely regulable and remains constant after being regulated.

I claim:

1. In a self-winding watch, a weighted pivoted lever, a second pivoted lever, a winding 20 train, means to impart uni-directional rotation from said second lever to a wheel in said winding train, and means resiliently connecting said levers.

2. In a self-winding watch, a weighted pivoted lever, a second pivoted lever, a winding train, means to impart uni-directional rotation from said second lever to a wheel of said winding train, and a resilient member carried by one of said levers and engaging the 30 other lever yieldably to maintain said levers in predetermined relationship.

3. In a self-winding watch, a weighted pivoted lever, a second pivoted lever, a winding train, means to impart uni-directional rotation from said second lever to a wheel of said winding train, a resilient member carried by one of said levers and engaging the other lever yieldably to maintain said levers in predetermined relationship, and means to 40 regulate the tension of said resilient member.

4. In a self-winding watch, a weighted pivoted lever, a second pivoted lever, a resilient member pivotally supported by one of said levers, a pin carried by the other lever and engaging one end of said resilient member, and adjustable means engaging the other end of said resilient member for varying the tension of the resilient member.

5. In a self-winding watch, a weighted pendulum, a pivoted lever, a winding train, means to impart uni-directional rotation from said lever to a wheel of said winding train, and means resiliently connecting said 55 pendulum and lever.

6. In a self-winding watch, a weighted pivoted lever, a second pivoted lever, a winding train, means to impart uni-directional rotation from said second lever to a wheel 60 of said winding train, a resilient member pivotally carried by one of said levers and having one end engaging the other lever yieldably to maintain said levers in predetermined relationship, and adjustable means engaging 65 the remaining end of said resilient member

to regulate the tension of said resilient member.

7. In a self-winding watch, a weighted lever, a second lever, a pivoted connection between said levers, a winding train, a ratchet wheel connected thereto, a pawl carried by said second lever and engaging said ratchet wheel, and resilient connections between said levers tending to cause unitary movement thereof.

8. In a self-winding watch, a weighted pivoted lever, a second pivoted lever, a winding train, means to impart uni-directional rotation from said second lever to a wheel in said winding train, and means carried by one of said levers and engaging the other lever normally to effect corresponding oscillation of said levers.

9. In a self-winding watch, a pivoted lever, a second lever pivoted to said first lever, a weight supported by one of said levers, a winding train, means to impart uni-directional rotation from one of said levers to a wheel of said winding train, and means resiliently connecting said levers.

10. In a self-winding watch, a pivoted lever, a weighted pendulum pivoted to said lever, a winding train, means to impart uni-directional rotation from said lever to a wheel of said winding train, and resilient means connecting said pendulum and lever.

11. In a self-winding watch, a pivoted lever, a pivoted pendulum, said lever and pendulum having their axes offset, a winding train, means to impart uni-directional rotation from said lever to a wheel of said winding train, and resilient means connecting said pendulum and lever.

12. In a self-winding watch, a pivoted lever, a pivoted pendulum coaxial with said lever, a winding train, means to impart uni-directional rotation from said lever to a wheel of said winding train, and resilient means connecting said pendulum and lever.

In testimony whereof, I have signed my name to this specification.

MAX REINER.
